UNITED STATES PATENT OFFICE.

DE VER H. WARNER, OF BRIDGEPORT, CONNECTICUT.

DESIGN FOR A HOLDER FOR GARMENT-SUPPORTERS.

SPECIFICATION forming part of Design No. 28,303, dated February 15, 1898.

Application filed December 9, 1897. Serial No. 661,322. Term of patent 14 years.

To all whom it may concern:

Be it known that I, DE VER H. WARNER, a citizen of the United States, residing in Bridgeport, in the county of Fairfield and State of Connecticut, have invented and produced a new and original Design for Holders of Garment-Supporters, of which the following is a specification.

My invention relates to a new and original design for holders of garment-supporters, of which the following is a specification, reference being had to the accompanying drawing.

The drawing is a plan view of a holder of a garment-supporter, embodying my new design.

In the drawing, A represents a holder-plate

of a generally pandurate outline, having a longitudinal opening a with curved edges and narrower at one end than at the other. The portion of the holder-plate surrounding the opening a has a perforated or reticulated or open fretwork configuration, as shown.

What I claim is—

The design for a holder of a garment-supporter, substantially as specified.

In testimony whereof I have signed my name to this specification in the presence of two subscribing witnesses.

DE VER H. WARNER.
